(57) **CLAIM**

The ornamental design for a barbecue grill shelf, as shown and described.

DESCRIPTION

FIG. 1 is a front, side perspective view for a barbecue grill shelf, showing my new design;

FIG. 2 is a top view thereof;

FIG. 3 is a bottom view thereof; and,

FIG. 4 is a second front, side perspective view thereof, shown in environmental use.

The broken lines in FIGS. 1-4 are for showing portions of the barbecue grill shelf and form no part of the claimed design.

1 Claim, 4 Drawing Sheets

FIG. 1

FIG. 2

FIG. 3
